UNITED STATES PATENT OFFICE

ADOLPH J. OBORSKI, OF CHICAGO, ILLINOIS

TOOL RETAINER

Application filed September 16, 1929. Serial No. 392,955.

My invention relates to devices for the retention of tools to prevent their loss, and more particularly to such devices as may be worn or carried by the mechanic to prevent the loss of such tools as calipers, scales and the like, and my main object is to provide a retainer which may be handily attached to the jumper, apron or overall suit worn by the mechanic.

10 A further object of the invention is to design the same with a number of receptacles particularly suitable for the customary tools carried in the breast pocket of the garment.

15 Another object of the invention is to construct the novel retainer with means exerting an inherent tension upon the articles retained to hold them with a firm grip.

20 A final but nevertheless important object of the invention is to construct the novel retainer of few and simple parts, whereby to make its production inexpensive and its use easy.

25 With the above objects in view, and any others which may suggest themselves from the description and claims to follow, a better understanding of the invention may be gained by reference to the accompanying drawing, in which—

30 Figure 1 is a perspective view of the novel retainer as in use;

Figure 2 is a plan view of the retainer on the larger scale, showing the positions of articles received thereby means of dotted lines;

35 Figure 3 is a front elevation of the view in Figure 2;

Figure 4 is a rear elevation of the retainer; and

Figure 5 is a cross-section on the line 5—5 of Figure 2.

40 In the average machine shop environment, the lathe or bench hand usually selects the calipers, the scale, and the pencil as the closest or most frequently used tools, and these he keeps in the breast pocket of the jumper or other work garment, so that they may be handily removed for use or replaced. Frequently, however, the worker stoops or bends down, such as to bring up an object or examine objects close to the floor, in which 45 event the articles carried in the breast pocket

are subject to drop and become damaged or lost; also, in changing the garment at lunch time, one or another article in the pocket may slide out and fall to the floor or drop into a pile of shavings or refuse and so become lost. 55 It is, therefore, appreciated that an article having the objects outlined above is a necessity.

Referring to the drawing in greater detail, it will be noted that I provide a base strip 10 as a foundation for the novel retainer, such strip being of firm sheet metal and preferably enlarged with scallops 10a to seat the retainer securely against the garment. The base plate is secured to the garment by a safety pin 11, the base of the pin being preferably held to the plate by hooks 12 struck from the plate and pressed into engagement with the pin base; and the keeper 13 for the pin may also be a strip struck 70 rearwardly from the base strip 10.

On the frontal side, the base plate receives a serpentine strip 14 of spring sheet metal, the strip being so formed that it has a large medial pocket for the head 15 of a long caliper 15a, a smaller pocket at one side for the ratchet screw 16 of a short caliper 16a, a pocket on the opposite side for a pencil 17 and pockets at the extreme ends for scales 18. 75

The medial pockets are rounded, since the parts they receive are cylindrical or substantially so; but the terminal pockets are narrow, since the scales are narrow strips of steel. The material at the bottom of the terminal pockets is squared to form heel portions 14c 85 flatly seating against the base plate and so stabilizing the strip relative to the same.

The strip 14 has a generally horizontal position, but its width is varied as indicated at 14a for purposes of ornamentation. Also, the entrances to the pockets are slightly constricted, as indicated at 14b, so that a slight amount of force would be required to insert the tools in the respective pockets, that they may be held therein with tension. The device is fastened to the garment at a point above the pocket, the height being suitable to receive the tools as indicated in Figure 3. 90

95 The retainer strip 14 is secured to the base strip by intermediate rivets 19, although spot 100

welding may be employed in preference to rivets. Outside the ends, the strip is retained by end pieces or tongues 20 struck forward from the ends of the base strip 10, these end pieces engaging the terminal sections 14d of the strip whereby to maintain the compression initially imparted to the strip for properly holding or retaining the tools. The end pieces 20 and the said terminal sections are in substantially vertical planes, affording alined seats for the terminal section against the end pieces and rendering the assembly firm.

It will be seen that the article described provides a simple method of holding the upper parts of the tools usually held in the pocket, so that when the worker stoops or discards the garment, the tools will not fall out and suffer damage or loss of adjustment when striking the floor or other surrounding objects, or become lost. The article is extremely light and easy to secure to the garment, and the retaining strip may be designed to exert the proper amount of tension whereby to firmly hold the tools in place, yet permit their easy removal if desired. Finally, the device is constructed of a minimum of parts, so that it may be produced at low cost.

I claim:

- 30 1. A tool retainer comprising a backing plate, a frontal spring strip of sinuous form and presenting a series of pockets separated by loops, and end pieces carried by the backing plate and clamping the strip in lineally compressed state.
2. The structure of claim 1, said end pieces being cut and struck forward from the ends of the plate.
3. A tool retainer comprising a backing plate, a frontal strip applied to the latter and shaped to present resilient tool clips, squared heel portions in the terminal regions of the strip and flatly seated against the plate to stabilize the strip relative to the latter, terminal sections projected from the heel portions, and end pieces carried by the plate and engaging the terminal sections to clamp the strip in lineally compressed state.
4. The structure of claim 3, said terminal sections being flat and in substantially vertical planes, and the end pieces also being flat and in substantially vertical planes for the alined seating of the terminal sections thereagainst.

55 In testimony whereof I affix my signature.
ADOLPH J. OBORSKI.
